MACHINE FOR MOUNTING RHINESTONES ON FABRIC

Anton Effgen, Westwood, Mass.

Filed Feb. 26, 1957, Ser. No. 642,438

6 Claims. (Cl. 1—3)

This invention relates to machines for feeding rhinestones and settings therefor to an operating station where they are mounted on a strip or sheet of cloth or other equivalent fabric. In general the machine is somewhat similar to that described and illustrated in U.S. Patent No. 2,747,185, granted May 29, 1956. The machine hereinafter described contains improvements in details of construction to enable it to mount rhinestones on fabric.

The rhinestones, which have a disk-like base with a flat truncated pyramid thereon are heaped in a hopper from which they are fed in succession down a chute or raceway after being properly oriented. The settings, which are of thin metal and consist of disks with upturned prongs, are fed from another hopper, properly oriented, into a chute. The rhinestones are simultaneously placed, one by one, on an anvil below the fabric and the settings are fed one by one to a position above the fabric and in line with the anvil. A plunger descends to crimp the prongs around the edge of the base of the stone.

The present invention relates more particularly to improvements in the mechanisms for automatically arranging rhinestones from a random heap in a hopper into a single line or series in which the stones are uniformly oriented, for feeding the stones one by one to an operating station, and for feeding metal settings for the stones to the same station.

For a more complete understanding of the invention reference may be had to the following description thereof and to the drawing of which—

Figure 1 is a side elevation of a machine embodying the invention;

Figure 2 is a plan view of the same;

Figure 3 is a section, on a larger scale, on the line 3—3 of Figures 1 and 2;

Figure 4 is a fragmentary section, on an enlarged scale, on the line 4—4 of Figure 3;

Figure 5 is a fragmentary section, on a larger scale, of one of the parts shown in Figure 4;

Figure 6 is a fragmentary elevation of the hopper for rhinestones showing a port and a rail extending therethrough;

Figure 7 is an elevational view of the upper portion of a narrow face of an agitator blade for the rhinestone hopper;

Figure 8 is an elevation of a broad face of the same;

Figure 9 is a portion of Figure 2 shown on a larger scale and in more detail;

Figure 10 is a fragmentary elevational view of the parts shown in Figure 9;

Figure 11 is a section on the line 11—11 of Figure 9;

Figure 12 is a section on the line 12—12 of Figure 9;

Figure 13 is a fragmentary plan view of the mechanism for feeding rhinestones into setting position;

Figure 14 is a side elevation of the same;

Figure 15 is a fragmentary side elevation of part of the mechanism shown in Figures 13 and 14;

2

Figure 16 is a plan view on a larger scale, of part of the mechanism shown in Figure 13;

Figure 17 is a perspective view of the same;

Figure 18 is a plan view of feeding mechanism for 5 settings;

Figure 19 is a section on the line 19—19 of Figure 18;

Figure 20 is an end elevation of the parts shown in 10 Figure 18;

Figure 21 is a plan view of the mechanism shown in

10 Figure 18 but at a different stage of operation;

Figure 22 is a section on the line 22—22 of Figure 21;

Figure 23 is an end elevation of the parts shown in 15 Figure 21;

Figure 24 is a magnified bottom plan view of a setting 20 for a rhinestone;

Figure 25 is a section on the line 25—25 of Figure 24; and

Figures 26 and 27 are fragmentary perspective views 25 of the upper portion of the blade shown in part in Figures 7 and 8, as viewed from a higher level.

The machine as a whole is illustrated in Figures 1 and 2 and is in many respects similar in construction and operation to the machine shown and described in United States Patent No. 2,747,185. The machine has a main frame including a base 10 supported at a suitable height above the floor by means not shown. A bin 12 is mounted above the table on an upright 14, and a bracket 16 on the table carries a head 18 in which is adjustably mounted a tubular guide member 20. The bin and its support

30 may be made as illustrated in United States Patent No. 2,489,764. Within the guide member 20 is a vertical plunger 22 which is above and aligned with a cylindrical anvil 24. The anvil is vertically slideable in a block 26 secured to an end of the table 10. Rhinestones and settings therefor are fed by means hereinafter described to an operating position between the plunger and the anvil. The plunger is then moved down toward the anvil to clinch the prongs of a setting over the circumferential edge of the rhinestone so as to affix the stone to a piece of sheet material which has previously been inserted between the plunger and the anvil.

To operate the movable members of the machine, including the plunger 22 and anvil 24, a vertical foot lever 30 is pivoted at 32 on the bracket 16 and extends down 45 below the base 10 to a treadle (not shown). The upper end of the lever 30 is connected by a link 34 to a rock-arm 36 secured on a short shaft 38 journaled in a bearing 40 which is a part of the bracket 16. Fixed on the shaft 38 to be rocked thereby is an elongated rock-arm 42 the upper end of which is operatively connected with the plunger 22 in the manner shown and described in said Patent No. 2,747,185.

The anvil 24 is cammed upward to its operative position by a cam member 44 the lower edge of which bears 50 on a fixed stud 46 carried by the block 26. The member 44 is horizontally reciprocated by the foot-lever 30 to which it is pivotally connected by a stud 48 which passes through both.

The bin 12 is adapted to hold a supply of metal settings 55 adapted to grip gems such as rhinestones. From the bin 12 a guide rail 52 slopes downward nearly to the operating station between the lower end of the plunger 22 and the anvil 24. Settings in the bin are lifted and deposited on the rail 52 by a blade (not shown) which is vertically reciprocated by rocking movement of the lever 42 acting 60 through a stud 54 mounted on the blade in the manner shown in said Patent No. 2,489,764. A cover 56 is mounted above the rail 52, the clearance between the cover and the rail being carefully adjusted to receive the settings which slide down on the rail but also to prevent any of the settings thereon from riding up on the setting immediately ahead.

The settings 50 are of thin metal stock and consist essentially of a disk 58 from the rim of which at least three spaced prongs 60 project perpendicularly, four such prongs being the customary number. The settings 50 slide down the rail in inverted position, straddling the rail with two prongs on either side. For reliable operation of the machine, the series of settings must slide down the rail 52 freely but without overlapping one another. For this purpose, the bottom of each setting is swaged to offset the central portion upward as indicated in Figure 25. This increases the virtual thickness of the bottom as a whole and also results in an accurate uniformity of such thicknesses. In making the settings it is preferred to shape the blanks with notches 62 at the base of each prong 60 so that the prongs can be bent up to their perpendicular position with less chance for distortion of adjacent portions of the bottom or disk 58 of the setting.

The lower end of the guide rail 52 is adjacent to the operating station. Beneath the lower end portion of the rail and pivoted thereto is a carrier arm 66, the lower end of which extends out beyond the lower end of the rail to receive a setting therefrom so as to support it at the operating station in the manner illustrated more fully in Patent No. 2,489,764, the arm 66 being yieldingly supported in its normally raised position by a spring 67. The leading setting on the rail 52 is cammed to the projecting portion of the carrier arm 66 by an L-shaped arm 68 which is pivoted at its upper end as at 70, the lower portion of the arm being arranged to extend across the lower end portion of the rail 52 just below the end of the cover 56. The arm 68 is swung to the advanced position shown in Figure 18 by descending movement of a lug 72 mounted on the lever 42, and is retracted to the position shown in Figure 21 by a suitable spring 74. A diagonal channel 76 in the under face of the arm 68 forms a dividing wedge 78 on the arm to come between the leading setting and the one next to it. Owing to the thinness of the stock of which the settings are made, the wedge 78 is not relied on to separate contiguous settings, the initial separation being brought about by gravity. To this end a light leaf spring 80 is mounted on the cover 56, the spring having a small finger 82 extending down therefrom through a notch in the cover 56 to bear frictionally on the setting which is next to the leading setting. When the arm 68 is retracted by the spring 74, the leading setting slides by gravity to engage the lower wall 84 of the channel 76 as soon as it is cleared by the wedge 78. The rest of the settings on the rail 52 are detailed by the finger 82 of the spring 80. The latter extends over and in contact with the lower portion of the arm 68. When the arm is swung to its advance position (Figures 18 and 20) the end portion of the spring 80 rides up on a thickened portion 86 of the arm 68 lifting the finger 82 and releasing the series of settings on the rail 52 to descend until stopped by the engagement of the now leading setting with the wedge 78.

A supply of rhinestones may be heaped in a hopper 90 attached to a side of the bin 12 or otherwise conveniently supported in an elevated position. An inclined guide rail 92 is against one inner wall face of the hopper and projects out and down through an adjacent wall 93 of the hopper. The upper edge surface 94 of the rail is transversely inclined at an angle of 60° or so and is wide enough to accommodate a single rhinestone. Along the lower side of the face 94 is a narrow flange 96 which is sufficient to retain a rhinestone on the face 94 when the bottom of the stone is against the face but will not retain a stone the top of which is against the face 94. The stone shown in Figure 5 is in an unstable position and is about to slip over the flange 96. As indicated in Figure 6, an aperture 98 is made through the wall of the hopper immediately above the rail 92, this aperture being shaped to permit passage therethrough of a stone sliding with its bottom surface on the face 94, but not otherwise.

This aperture or port 98 prevents the passage from the hopper of stones which are not properly oriented.

To deposit rhinestones on the rail 92, a loading blade 100 projects up into the hopper for vertical reciprocation. The blade is operatively connected to the stud 54 by an arm 102 which is pivoted at 104 and rocked by movements of the stud, and a link 106 which extends from the lower end of the blade 100 and is pivotally connected to the arm 102. As rhinestones are fragile, the contour of the upper end of the blade 100 is important to avoid crushing the stones when the blade is operated.

The blade preferably has a rectangular horizontal cross-section, and has two relatively broad faces and two relatively narrow faces. One of the broad faces 108 slides on a side face of the portion of the rail 92 which is within the hopper 90. The high point 110 of the top of the blade 100 is at the corner adjacent to the port 98 where the rail extends through the wall 93. The top of the blade has a sloping face 112 facing the rail 92, this face being somewhat concaved so that it tapers in width from an intermediate portion thereof to the point 110 (Figure 8) at one end and to a lower point 114 at the other end.

The face 112 is bounded on its lower side by its dog-leg intersection 116 with a broad side face of the blade and on its upper side by a dog-leg ridge crest 118. A smaller triangular face 120 (Figures 2 and 3) at the top of the blade slopes downward from the high point 110, and a more steeply sloping face 122 completes the top surface of the blade.

When the machine is in operation, the blade 100 reciprocates vertically between a low position in which the high point 110 is below the port 98, and a high position in which the point 110 is well above the level of the port 98. A baffle 124 in the hopper prevents the stones from piling up too deeply over the top of the blade. As the blade rises from its low position, the point 110 and ridge crest 118 plow up through the overlying stones; pushing a few of them toward the rail face 94 and deflecting the rest of them away from the rail. If when the blade starts to rise a stone is blocking the port 98 because it is wrongly oriented the portion of the face 112 adjacent to the point 110 will cam the stone away from the port so that another can take its place. Most of the stones in that part of the hopper will be shunted away from the rail, the relatively few which are lifted by the face 112 being deflected onto the face 94 of the rail. When the blade 100 descends, the stones on the face 94 are left without support from the blade. The stones which are properly oriented on the rail will stay there and will slide toward the port. The others will fall off.

The inclined rail 92 guides the stones thereon to a raceway 130 which inverts the stones and guides them to the operating station where they are to be affixed to a fabric. As shown, the raceway extends steeply downward and then slopes to the operating station, the stones sliding face downward on the latter portion. The raceway consists of a bar having a longitudinal channel 132 wide enough and deep enough to accommodate a succession of stones under a cover 133 thereon. This cover is preferably of transparent plastic material so that the stones in the channel can be easily inspected. When a broken stone or fragment is noticed in the raceway, it can be removed through a gateway 134 in the side of the raceway provided for that purpose. The gateway is normally closed by a block 136 which is held in place by a headed screw 138. When the screw is loosened and the block allowed to drop to the position shown in Figures 10 and 11, the gateway 134 is for the removal of stones or fragments thereof from the raceway. To reduce the chances of the stones being retarded or stopped by accumulations of dust, lint or the like in the channel 132, narrow grooves 140 extend downward at the margins of the channel, defining a central rail 142 on which the top face of each stone bears. For the escape of dust etc.

from the grooves 140, any desired number of notches 144 are cut through the side walls of the raceway to open into the grooves at a level not higher than the bottom of the channel, two such notches being indicated in Figure 2.

At its lower end, the raceway 130 terminates at a point adjacent to the operating station above the anvil 24. Opposite the end of the channel in the raceway is a small block 148 which is set into the block 26. In one edge face of the block 148 is a groove in which is slidably fitted a rod 150 having a nose 152 normally projecting beyond the adjacent side of the block into the path of the leading stone of the series in the raceway 130. The nose 152 acts as a yielding detent for the leading stone, the rod 150 being pressed at its other end by a light spring 154. A push-rod 156 is provided to push the leading stone from the position shown in Figure 16 to the operating station over the anvil. The push-rod 156 is mounted on a slide 158 which runs in ways in the block 26. A spring 160 in the block 26 presses the slide 158 away from the operating station. A turn-button 162 on a rocking member 164 operates to push the slide 158 and the push-rod 156 forward to move a stone to the operating station. To keep the stone from jumping out of place when it is propelled by the push rod, a light leaf spring 166 is mounted over the rod and projects beyond the end thereof far enough to extend over the anvil when the push-rod is projected forward to move the leading setting to the operating station. The rocking member 164 is pivoted at 170 to a frame member 172 extending down from the base 10. A stud 174 on the member 164 rides on a cam 176, which is a part of the cam member 44, when the latter is advanced (to the left as in Figure 14) by the stud 48.

The operation of the machine is as follows. When the moving parts are in the positions shown in Figure 1, the machine is ready to receive a strip or sheet of fabric (not shown) which may be held so that the portion to which a stone is to be affixed is in the operating position, that is, in the space between the aligned plunger 22 and anvil 24. At this time the plunger 22 is up, the anvil 24 is down, the picker arm 68 is in the retracted position shown in Figure 21, the cam member 44 is in its advanced position, the pusher-rod 156 is in its advanced position, having pushed a stone forward into alignment between the plunger 22 and the anvil 124, and the loading blades in the bin 12 and the hopper 90 are down.

When the fabric is in place at the operating station, the treadle is kicked to swing the lever 30 to the rear. This causes the picker arm 68 to swing to the advanced position shown in Figure 18, thus moving the leading setting into line between the plunger 22 and the anvil 24 at a point above the stone which has previously been pushed into place and the fabric which is held at the operating station, the cam member is retracted, causing the anvil to rise with an inverted stone thereon, the spring 166 is retracted from the operating station, the loading blades rise, and the plunger 22 descends to drive the prongs of the setting on the carrier arm 66 through the fabric to be clinched by the anvil about the margin of the stone resting on the anvil. The swing of the picker arm 68 to its advanced position cams the spring 80 upward so that the finger 82 is lifted clear of the settings which thereupon advanced a distance equal to the diameter of a setting, the leading setting coming against a side of the wedge 78.

When the lever 30 returns to the position shown in Figure 1, the rock-arm 42 is rocked thereby to elevate the plunger 22 and lower the loading blades in the bin and hopper. The picker arm 68 swings back to the retracted position shown in Figure 21, allowing the spring finger 82 to engage the second setting in the series while the leading setting is cleared by the wedge 78 to slide down into the channel 76 ready to be discharged onto the carrier arm 66. The cam member 44 is moved

forward to allow the anvil to drop to its lower position, and the rocking member 164 is rocked forward to advance the pusher-rod 156 which pushes the next stone into position above the anvil.

In the foregoing operation the stones and settings are advanced to the operating station in inverted positions, the setting being above the stone. The fabric to be ornamented is therefore held with its front face down so that the stones will be affixed to that face. If, however, it is desired to use the settings themselves or similar objects such as "nail-heads" as the ornamenting elements, the fabric is held with its front face up and no stones are fed to the operating station. The omission of the stones can be readily had by turning the turn-button 162 to the position shown in broken lines in Figure 13. When the turn-button is in that position, the pusher-rod remains in its retracted position and no stone is pushed past the detent nose 152.

I claim:

- 20 1. In a machine for affixing rhinestones to a fabric, a hopper for a supply of rhinestones, an inclined feed rail extending through a side of said hopper, said rail having a transversely inclined top face wider than the diameter of a rhinestone and a narrow flange along the lower edge 25 of said top-face, a vertically reciprocal blade having its upper portion within said hopper and face to face against the flanged side of said rail, said blade having a top portion with a face inclined toward said rail, said inclined face of said blade being concave and tapering in width in 30 both directions from an intermediate portion of maximum width, and means for reciprocating said blade from and to a low position in which its top is below the level of said top face.
2. A loading blade adapted for vertical reciprocation in 35 a hopper, said blade having broad front and rear faces and narrow side faces, the top of said blade having two corners at said front face and an inclined face extending from one said corner to the other, said inclined top face varying in width from a maximum at its medial portion to 40 minima at said corners.
3. A loading blade as in claim 2, the highest point of said top being at one of said front corners.
4. In a machine for affixing rhinestones to fabrics, said 45 machine including a frame, an anvil carried by said frame, and a raceway for rhinestones terminating at a point adjacent to said anvil; a fixed block adjacent to said anvil and the end of said raceway, a reciprocable pusher-rod extending toward said anvil between said block and the end of said raceway, a spring-pressed detent element carried by said block in a position to stop the leading rhinestone of a series of stones guided by said raceway in a position between the end of said pusher-rod and said anvil, and means carried by said frame for reciprocating said pusher-rod to push the leading rhinestone from its position 50 against said detent element to an operating station over said anvil.
5. In a machine for affixing rhinestones to fabric, said 55 machine including a frame, an anvil carried by said frame, and a raceway for rhinestones terminating at a point adjacent to said anvil; a fixed block adjacent to said anvil and the end of said raceway, a reciprocable pusher-rod extending toward said anvil between said block and the end of said raceway, a light leaf spring mounted on said pusher-rod and projecting beyond the end thereof to press 60 lightly on the rhinestone which is pushed by the rod, a spring-pressed detent element carried by said block in a position to stop the leading rhinestone of a series of stones guided by said raceway in a position between the end of said pusher-rod and said anvil, and means carried by said frame for reciprocating said pusher-rod to push the leading rhinestone from its position against said detent element to an operating station over said anvil.
6. In a machine for affixing rhinestones to fabrics, a 65 raceway for guiding a series of metal settings for rhine-

stones, a picket member reciprocable between advanced and retracted positions across the delivery end portion of said raceway, said member having a stop portion engageable by the leading setting in the raceway when the member is in its advanced position, said stop portion being out of the path of said leading setting when the member is in its retracted position, said member having a secondary stop portion in the path of said leading setting when the member is retracted, and a spring pressed finger bearing frictionally on the setting next to the leading setting when the member is in its advanced position, said member having a cam portion lifting said finger when the member moves to its retracted position.
